AUTOMOBILE SERVICE RAMP

Jack V. Miller, 700 N. Auburn Ave.,
Sierra Madre, Calif. 91024

Filed Nov. 4, 1974, Ser. No. 520,566

Term of patent 14 years

Int. Cl. D12—05

U.S. Cl. D12—53

FIG. 1

FIG. 2

FIG. 4

FIG. 3

FIG. 5

FIG. 1 is a perspective view of the automobile service ramp showing my new design:

FIG. 2 is a top plan view thereof;

FIG. 3 is a side elevational view thereof, the opposite side being a mirror image of the side shown herein;

FIG. 4 is a front elevational view thereof; and

FIG. 5 is a rear elevational view thereof.

I claim:

The ornamental design for an automobile service ramp, substantially as shown.
